DESIGN FOR A BOWL

Jamie E. Matchet, Newark, Ohio, assignor to Verlys of America, Inc., New York, N. Y., a corporation of New York

Application October 17, 1936, Serial No. 65,343

Term of patent 7 years

To all whom it may concern:

Be it known that I, Jamie E. Matchet, a citizen of the United States of America and a resident of Newark, in the county of Licking and State of Ohio, have invented a new, original, and ornamental Design for a Bowl, of which the following is a specification, reference being had to the accompanying drawing, forming a part hereof.

Fig. 1 is a side elevational view of a bowl, showing my new design, and

Fig. 2 is an inverted plan view thereof.

I claim:

The ornamental design for a bowl, as shown.

JAMIE E. MATCHET.
